DESIGN FOR A DRYING RACK FOR DISHES, GLASSES, VEGETABLES, FRUITS, OR THE LIKE

Harry J. Tinney, Wyandotte, Mich., assignor of
one-half to Edgar B. Reichert Detroit, Mich.

Application January 8, 1942, Serial No. 105,077

Term of patent 7 years

To all whom it may concern:

Be it known that I, Harry J. Tinney, a citizen of the United States, residing at Wyandotte, in the county of Wayne and State of Michigan, have invented a new, original, and ornamental Design for a Drying Rack for Dishes, Glasses, Vegetables, Fruits, or the like, of which the following is a specification, reference being had to the accompanying drawing, forming a part thereof, in which:

Fig. 1 is a top plan view of a drying rack for dishes, glasses, vegetables, fruits or the like showing my new design;

Fig. 2 is a side elevational view thereof;
Fig. 3 is an end elevational view taken from the left of Fig. 2; and

Fig. 4 is an enlarged detailed fragmentary sectional view taken on the line 4—4 of Fig. 1.

I claim:

The ornamental design for a drying rack for dishes, glasses, vegetables fruits or the like, substantially as shown.

HARRY J. TINNEY,
